WINGLESS AIRCRAFT

Alexander M. Lippisch, Cedar Rapids, Iowa, assignor to
Collins Radio Company, Cedar Rapids, Iowa, a corpora-
tion of Iowa

Application November 26, 1954, Serial No. 33,264

Term of patent 14 years

(Cl. D71—1)

FIG 1

FIG 2

FIG 3

Figure 1 is a side elevational view of a wingless aircraft showing my new design,

Figure 2 is a top plan view,

Figure 3 is a rear end view.

The opposite side of the aircraft is of substantially the same appearance to that seen in Figures 1 and 2, being symmetrical about a vertical longitudinal plane through the aircraft.

I claim:

The ornamental design for a wingless aircraft, as shown and described.
